CLAIM

The ornamental design for a protective barrier pole, as shown and described.

DESCRIPTION

FIG. 1 is a perspective view of a protective barrier pole showing the claimed design;

FIG. 2 is front elevation view thereof;

FIG. 3 is a back elevation view thereof;

FIG. 4 is a right side elevation view thereof;

FIG. 5 is a left side elevation view thereof;

FIG. 6 is a top view thereof; and,

FIG. 7 is a bottom view thereof.

The dash-dot broken lines depict the boundaries of the claim and form no part thereof. The dash-dash broken lines depict environmental subject matter and form no part of the claim. The drawings contain symbolic break lines in FIGS. 1-5. Any portion between the break lines forms no part of the claimed design.
